TRIGGER-TYPE GASEOUS BLOWTorch

Filed July 5, 1947

Fig. 1

UNITED STATES PATENT OFFICE

2,506,114

TRIGGER-TYPE GASEOUS BLOWTORCH

Warren A. Sparks, Long Beach, Calif., assignor
to John M. Henry, Inglewood, Calif.

Application July 5, 1947, Serial No. 759,065

11 Claims. (Cl. 158—27.4)

1

This invention relates to a gas burner or automatic acetylene torch, and more particularly to such a torch designed to light a stream of mixed air and acetylene gas on the snap of a trigger and in its more specific aspects to an improvement in the gas-air mixing and controlling mechanism for such a torch.

While there have been hitherto proposed acetylene torches adapted to ignite a proper mixture of acetylene gas and air upon the snap of a trigger by the action of flint on steel, these devices have not met with the expected trade acceptance because of the fact that they have not been adaptable to the various types of flame desired in torches of this kind and because the gas-air mixing mechanism has not been readily removable for replacement with mechanism more suitable for the various operations desired.

It is accordingly a primary object of this invention to provide in a torch of the type described means for quickly and readily removing the gas-air mixing and controlling parts for replacement.

It is another object of this invention to render such torches more versatile by adapting them for such replacement.

It is a further object of this invention to facilitate assembly and disassembly of such torches and consequently to render their manufacture more economical.

It is a further object of this invention to provide such a torch which automatically lights the flame on the snap of the trigger, automatically extinguishes the flame on release of the trigger, is simple, light and durable of construction, and by reason of its easily replaceable combustion tubes is equally adaptable for soldering, silver soldering, fine light brazing, or lead burning.

Further objects and advantages will be apparent from the annexed specification, in which:

Figure 1 is a side view, mostly in section along a vertical line, of a torch embodying the present invention; and

Figure 2 is an enlarged section taken along the line 2—2 of Figure 1.

Referring now more particularly to the drawings, there is shown an acetylene torch including a body 10 which may be die-cast and is generally composed of two pieces, one being as shown in section in Figure 1 and in practice continuing beyond the section line slightly beyond the mid-line of the body and the other, a complementary portion, not shown, adapted to be secured to the first after assembly of the remainder of the torch by means of the rivets shown.

The body 10 includes a pistol grip 12 having 55

2

a hollow interior 13 and extends upwardly to form the upper portion 14 and the trigger-receiving portion 16. The body 10 is bored as at 17 which bore is tapped as at 18 to receive the threaded end 5 20 of a gas inlet tube 21. The gas inlet tube 21 may be affixed in the hollow interior 13 of the pistol grip 12 by a close fit in an aperture 22 formed in the butt plate 23 secured to the shoulder 24 formed in the lowermost end of the pistol grip 12. The end of the tube 21 extending downward through the butt plate 23 is serrated as at 10 25 to receive a gas hose 26 which may lead to any suitable source of acetylene gas under pressure.

A lateral bore 28 is formed in the portion 14 15 of the body 10 and is tapped as at 30 to receive the threaded portion 31 of a valve cover screw 32. The valve cover screw 32 is counterbored as at 33 to receive one end of a valve spring 34. The valve cover screw 32 has an enlarged head 36 20 providing a shoulder against which is held a rubber gasket 37 preventing leakage of gas through the valve cover screw when securely seated in the bore 33. The bore 28 is beveled as at 38 to form a seat for the gasket 37 for this purpose.

The valve cover screw 32 is reduced as at 40 25 and again at 41 and the reduced portion 41 forms a shoulder against which abuts the end of a valve housing 43. The valve housing 43 has an outer diameter less than the interior diameter of the bore 33, is bored as at 44, and is provided with a smaller communicating bore 45. A valve stem 47 is provided in the bore 45 and has a valve member 48 formed thereon beyond which the valve stem 47 extends into the bore 44, forming 30 a receiving post for the other end of the valve spring 34. Between the valve member 48 and the end of the bore 44 is positioned a rubber gasket 49. The valve housing 43 is provided with a groove 51 in which is seated a rubber O ring 52 35 and a semicircular groove 53 is formed on the housing 43. A hole 54 is drilled diametrically through the housing 43 in the center of the groove 53 and communicating with the bore 45. Furthermore, the valve stem 47 has an outer diameter 40 slightly less than the inner diameter of the bore 45.

The valve housing 43 is also provided with one or more holes 55 drilled through the housing opposite the closed position of the valve member 48 and communicating the bore 17 with bores 44 and 45 when the valve member 48 is in open position. The valve housing 43 has a dished end 56 bearing against a rubber diaphragm 57 which is seated in the end of the bore 28. A bore 58 is formed in the body 10 aligned with the bore 28, and a valve

plunger 59 is positioned therein with its inner end bearing on the rubber diaphragm 57. The outer end of the valve plunger 59 extends into the trigger-receiving portion 16 of the body 10 and abuts a toggle bar 60. The toggle bar 60 is channel-shaped and is pivoted on a rivet 61 in the trigger-receiving portion 16. A trigger 63 is pivoted on a rivet 64 and is also generally channel-shaped providing a channel 65 in which lies one end of a single coil trigger spring 66. The coil 67 of the spring 66 may extend partially into the channel in the toggle bar 60 as shown, and the walls of the trigger are extended laterally opposite the toggle bar 60 forming a trigger cam 68 engaging said toggle bar. The other end of the trigger spring 66 is bent downwardly as at 69 and engages the rear wall 70 and upper wall 71 of the trigger-receiving portion 16 of the body 10.

A notch 72 is ground in the upper portion of the trigger 63 which is adapted to be engaged by the rear end of an actuating bar 73. The actuating bar 73 extends out of the body 10 and is pivoted on a pin 74 in the channel-shaped extension 75 of the muzzle 76.

The forward wall of the trigger-receiving portion 16 is formed by a pair of spaced walls, one only of which, numbered 71, is shown, and the rearward edges of these walls are disposed at an obtuse angle to the upper wall 71 forming an inclined plane against which bears the beveled forward end of a washer 78. The washer 78 is positioned on the actuating bar 73, and a coiled compression spring 79 is also positioned on the actuating bar having one end biased against the washer 78 and the other end biased against a pin 80 in the actuating bar 73. A trip pin 81 is provided in the trigger-receiving portion 16 which also serves as a trigger stop.

A bore 82 is formed in the upper portion 14 of the body 10 which bore communicates with the groove 53 in the valve housing 43. A lateral bore 83 is formed in the upper portion 14 communicating with the bore 82, and an indexing pin 84 traverses the bore 83 as indicated. The bore 83 is enlarged as at 85 forming a shoulder 86. A tubular draw nut bearing 88 is mounted in a bore 89 aligned with the bore 83, and a draw nut 90 is mounted thereon lying in an enlarged portion 91 of the bore 83. The upper portion 14 of the body adjacent the draw nut 90 is relieved as at 92 for access to the draw nut 90 by the fingers of the operator. The draw nut 90 has a rearwardly extending flange 93 which is provided with female threads 94.

The draw nut bearing 88 extends beyond the end of the upper portion 14 of the body and forms a guide for a lateral bore 95 formed in the muzzle 76. The muzzle 76 is provided with a muzzle bushing 96 positioned in the bore 95 and the outer end of the muzzle bushing 96 is threaded as at 97 to receive the female threads 98 of the flame nozzle 99. A combustion tube 100 is provided which is adapted to be received in the bushing 96, the draw nut bearing 88, the draw nut 90, and the bore 83. The combustion tube 100 has a portion cut away as at 101, and in the upper portion of the combustion tube 100 opposite the cut-away portion 101 a serrated hard steel strip 102 is riveted.

The combustion tube 100 has a plurality of air intake holes 103 formed therein, and the rearward end of the combustion tube is threaded as at 104 for engagement with the female threads 94 of the draw nut 90. The combustion tube 100 is provided with an indexing tube 105, one end 75

106 of which has a portion cut away to underlie the indexing pin 84 when in position. The indexing tube 105 is provided at its forward end with a metering jet 107 which metering jet has its nozzle lying substantially in the plane of the rearward edges of the air intake holes 103. A rubber washer 108 is provided on the rearward end 106 of the indexing tube 105 and abutting the rearward end of the combustion tube. The rubber washer 108 is thus adapted when in position to engage the shoulder 86. The muzzle 76 is provided with a pair of air intake holes 110 and 111, and the upper portion 14 of the body is provided with an air intake hole 112 aligned with the hole 111 when the muzzle is in the rearward position, as shown in Figure 1.

The muzzle 76 has a downward extension 113 which has a bore 114 the upper end 115 of which is reduced and tapped to form the threads 116. A flint channel 117 is provided in the bore 114 and carries a rubber gasket 118 adapted to seat on the shoulder formed by the reduced bore 115. The flint channel 117 has a reduced and externally threaded portion 119 adapted for engagement with the threads 116. The flint channel 117 is provided with an upper tubular extension 120 and the flint channel 117 is also provided with an internal bore 121 in which lies a coiled spring 122 one end of which will abut the flint 123 and the lower end of which will abut the upper end 124 of a flint tension screw 125 which is received in an enlarged and internally threaded bore in the flint channel 117.

While there has been indicated a particular combustion tube 100 having a particular metering jet 107, it will be appreciated that the invention is adapted for a plurality of such interchangeable combustion tubes each designed for its particular type of flame best suited for its particular type of operation, such as soldering, silver soldering, fine light brazing, or lead burning. In the event that the operator wishes to change combustion tubes, it is necessary first to withdraw the flint 123 and flint channel 117 which is done simply by unscrewing the flint channel by means of the knurled knob 126. Next the operator removes the flame nozzle 99 simply by unscrewing it from the muzzle bushing 96 by means of the knurled portion 127. When this operation is completed, the operator then unscrews the draw nut 90 forcing the combustion tube 100 forwardly until the combustion tube is freed of the draw nut entirely and may be simply pulled out of the muzzle bushing. This sequence of operations may be then reversed with any particular one of the interchangeable combustion tubes desired, thus readily adapting the gun for a specific intended use without the necessity of using any tools whatsoever.

The operation of the gun is as follows: With the gun assembled and having the combustion tube desired for the particular operation, the operator depresses the trigger 63. The depressing of the trigger 63 causes the cam 68 to rock the toggle bar 60 in a clockwise direction, thus forcing the valve plunger 59 rearwardly. The valve plunger 59 engages the rubber diaphragm 57 which in turn engages the valve stem 47 and presses it rearwardly against the force of the valve spring 34. As this is done the valve member 48 uncovers the hole 55 and permits gas from the hose 26 and the tube 21 to enter the bore 45, the hole 54, the groove 53 and the bore 82. From there the gas is communicated to the bore 83 and the metering jet 107 and into the

combustion tube 100. Air will be mixed with the gas through air intake holes 103, 110, 111, and 112, and the combustible mixture of air and gas will pass through the combustion tube and past the flint 123 and steel 102 becoming ignited by the action of the flint and steel as hereinafter described, after which the flame issues through the flame nozzle 99.

When the trigger 63 is depressed as aforesaid, the upper portion thereof having the notch 72 is moved in a clockwise direction, thus forcing the actuating bar 73 forwardly until the notch 72 approaches the trip pin 81. At this point the actuating bar 73 is forced free of the notch 72 and the muzzle 76 is snapped into the rearward position under the force of the coiled spring 79. This snap action causes the flint 123 to be scraped forcibly against the steel 102 thus causing an igniting spark. The inclined plane formed by the walls, one of which 77 is shown, and the beveled end of the washer 78 causes a component of the force of the spring 79 to exist biasing the actuating arm in a counterclockwise direction, thus causing the rearward end of the actuating arm 73 to seek to re-engage the notch 72 on the trigger as soon as the trigger is released.

It will be apparent that the gas supply will continue and thus the flame will continue to burn as long as the trigger 63 is depressed, and in order to avoid the necessity of the operator continually exerting force to depress the trigger 63 a trigger lock 130 is provided in the form of a hook pivoted from the body 10 which can be hooked around the trigger 63 to hold it in the depressed position. When the trigger 63 is released, the valve spring 34 will cause the valve member 48 to close, thus shutting off the supply of gas and extinguishing the flame.

The upper portion 14 of the body may be provided with a bore 131 threaded as at 132 to receive a plug 133 thus forming a chamber for the retension of spare flints 134.

While there has been described what is at present considered a preferred embodiment of the invention, it will be apparent to those skilled in the art that various modifications and changes may be made therein without departing from the true scope and spirit of the invention, and it is intended to cover herein all such changes and modifications as come within the true spirit and scope of the appended claims.

What is claimed is:

1. An acetylene torch comprising a body member having a pistol grip, gas passage means in said body member and a valve disposed in one of said passages, a trigger operatively connected to said valve to open said valve on pulling of said trigger, said trigger having a snap action, a sealed upper body member having gas passages communicating with said first mentioned gas passages, a draw nut mounted in said upper body, a removable combustion tube mounted in said upper body and drawn into fluid-tight seal therewith by said draw nut, air inlet passage means in said upper body member and said combustion tube, a muzzle mounted on said combustion tube, flint-carrying means mounted in said muzzle, a striker mounted in said combustion tube and engageable by said flint, and means for moving said muzzle relative to said combustion tube on the snap of said trigger to strike a spark from said flint and ignite said torch.

2. An acetylene torch comprising a body member having a pistol grip, gas passage means in said body member and a valve disposed in one

of said passages, a trigger operatively connected to said valve to open said valve on pulling of said trigger, said trigger having a snap action, a sealed upper body member having gas passages communicating with said first mentioned gas passages, a removable combustion tube mounted in said upper body and means for drawing said combustion tube into fluid-tight seal with said upper body, air inlet passage means in said upper body member and said combustion tube, a muzzle mounted on said combustion tube, flint-carrying means mounted in said muzzle, a striker mounted in said combustion tube and engageable by said flint, and means for moving said muzzle relative to said combustion tube on the snap of said trigger to strike a spark from said flint and ignite said torch.

3. An acetylene torch comprising a body member having a pistol grip, gas passage means in said body member and a valve disposed in one of said passages, a trigger operatively connected to said valve to open said valve on pulling of said trigger, said trigger having a snap action, a sealed upper body member having gas passages communicating with said first mentioned gas passages, a draw nut mounted in said upper body, a removable combustion tube mounted in said upper body and drawn into fluid-tight seal therewith by said draw nut, a gas jet in said combustion tube, air inlet passage means in said upper body member and said combustion tube, a muzzle mounted on said combustion tube, flint-carrying means mounted in said muzzle, a striker mounted in said combustion tube and engageable by said flint, and means for moving said muzzle relative to said combustion tube on the snap of said trigger to strike a spark from said flint and ignite said torch.

4. An acetylene torch comprising a body member having a pistol grip, gas passage means in said body member and a valve disposed in one of said passages, a trigger operatively connected to said valve to open said valve on pulling of said trigger, said trigger having a snap action, a sealed upper body member having gas passages communicating with said first mentioned gas passages, a removable combustion tube mounted in said upper body and means for drawing said combustion tube into fluid-tight seal with said upper body, a gas jet in said combustion tube, air inlet passage means in said upper body member and said combustion tube, a muzzle mounted on said combustion tube, flint-carrying means mounted in said muzzle, a striker mounted in said combustion tube and engageable by said flint, and means for moving said muzzle relative to said combustion tube on the snap of said trigger to strike a spark from said flint and ignite said torch.

5. An acetylene torch comprising a body member having a pistol grip, gas passage means in said body member and a valve disposed in one of said passages, a trigger operatively connected to said valve to open said valve on pulling of said trigger, said trigger having a snap action, a sealed upper body member having gas passages communicating with said first mentioned gas passages, a draw nut mounted in said upper body, a removable combustion tube mounted in said upper body and drawn into fluid-tight seal therewith by said draw nut, a gas jet in said combustion tube, air inlet passage means in said upper body member and said combustion tube, said air inlet passages being normally disposed in a plane adjacent said gas jet, a muzzle mounted on said

combustion tube, flint-carrying means mounted in said muzzle, a striker mounted in said combustion tube and engageable by said flint, and means for moving said muzzle relative to said combustion tube on the snap of said trigger to strike a spark from said flint and ignite said torch.

6. In an acetylene torch of the type comprising a body, gas passage means in said body, and a valve in said body adapted to be actuated by a trigger, the improvement comprising: a horizontal bore in the upper body of said torch, a removable combustion tube mounted in said horizontal bore, means for drawing said removable combustion tube into fluid-tight seal with said bore, a muzzle telescopically mounted on said combustion tube, said muzzle having an aperture, flint-carrying means mounted in said aperture, a striker mounted in said tube engageable by said flint, and means defining air intake apertures in said upper body and said combustion tube.

7. In an acetylene torch of the type comprising a body, gas passage means in said body, and a valve in said body adapted to be actuated by a trigger, the improvement comprising: a horizontal bore in the upper body of said torch, a removable combustion tube mounted in said horizontal bore, a draw nut mounted in said upper body adjacent said bore and adapted to draw said combustion tube into fluid-tight seal with said bore, a muzzle telescopically mounted on said combustion tube, said muzzle having an aperture, flint-carrying means mounted in said aperture, a striker mounted in said tube engageable by said flint, and means defining air intake apertures in said upper body and said combustion tube.

8. In an acetylene torch of the type comprising a body, gas passage means in said body, and a valve in said body adapted to be actuated by a trigger, the improvement comprising: a horizontal bore in the upper body of said torch, a removable combustion tube mounted in said horizontal bore, a gas jet in said combustion tube, means for drawing said removable combustion tube into fluid-tight seal with said bore, a muzzle telescopically mounted on said combustion tube, said muzzle having an aperture, flint-carrying means mounted in said aperture, a striker mounted in said tube engageable by said flint, and means defining air intake apertures in said upper body and said combustion tube.

9. In an acetylene torch of the type comprising a body, gas passage means in said body, and a valve in said body adapted to be actuated by a trigger, the improvement comprising: a horizontal bore in the upper body of said torch, a re-

movable combustion tube mounted in said horizontal bore, a gas jet in said combustion tube, a draw nut mounted in said upper body adjacent said bore and adapted to draw said combustion tube into fluid-tight seal with said bore, a muzzle telescopically mounted on said combustion tube, said muzzle having an aperture, flint-carrying means mounted in said aperture, a striker mounted in said tube engageable by said flint, and means defining air intake apertures in said upper body and said combustion tube.

10. In an acetylene torch of the type comprising a body, gas passage means in said body, and a valve in said body adapted to be actuated by a trigger, the improvement comprising: a horizontal bore in the upper body of said torch, a removable combustion tube mounted in said horizontal bore, a gas jet in said combustion tube, means for drawing said removable combustion tube into fluid-tight seal with said bore, a muzzle telescopically mounted on said combustion tube, said muzzle having an aperture, flint-carrying means mounted in said aperture, a striker mounted in said tube engageable by said flint, and means defining air intake apertures in said upper body and said combustion tube normally disposed in a plane adjacent said gas jet.

11. In an acetylene torch of the type comprising a body, gas passage means in said body, and a valve in said body adapted to be actuated by a trigger, the improvement comprising: a horizontal bore in the upper body of said torch, a removable combustion tube mounted in said horizontal bore, a gas jet in said combustion tube, a draw nut mounted in said upper body adjacent said bore and adapted to draw said combustion tube into fluid-tight seal with said bore, a muzzle telescopically mounted on said combustion tube, said muzzle having an aperture, flint-carrying means mounted in said aperture, a striker mounted in said tube engageable by said flint, and means defining air intake apertures in said upper body and said combustion tube normally disposed in a plane adjacent said gas jet.
